United States Patent Office.

JOHN B. JOHNSON, OF LAUREL, INDIANA.

Letters Patent No. 72,402, dated December 17, 1867.

IMPROVEMENT IN FENCE.

The Schedule referred to in these Letters Patent and making part of the same.

TO ALL WHOM IT MAY CONCERN:

Be it known that I, JOHN B. JOHNSON, of Laurel, in the county of Franklin, and State of Indiana, have invented a new and useful Improvement in Fences; and I do hereby declare that the following is a full, clear, and exact description of the same, reference being had to the annexed drawings, making part of this specification, in which—

Figure 1 is a perspective view, and

Figure 2 is a side elevation.

The same letters are employed in both figures to indicate the same parts.

The object of this invention is to provide a cheap mode of constructing portable fences, particularly adapted for lands subject to overflow, by being so arranged that it may yield to the pressure of a current of water, and, remaining in place, may be easily restored to position on the subsiding of the water.

Posts, B, are inserted in the ground to a depth sufficient to give them stability, the upper end projecting, say, one foot above the ground. The panels are formed of posts, D, to which are nailed the boards F'. The panels are made separately, each one being independent of the others. These panels are fastened to the posts B, placed at proper distances from one another, by strong pins, B', passing through the posts B, and these through the end posts of the panels D, on one or both sides of the posts B. The panels are maintained in a vertical position by braces, E, extending from their top to posts A, inserted in the ground. The braces are fastened to the posts A by pins A', and to the upper end of the panel-posts D by wooden pins C, which are much weaker than the pins B', which may be also of wood or of iron.

It will be observed that a fence thus constructed may be very easily set up. Should it be exposed to the action of a current of water sufficient to injure it, the pins C, being the weakest part of the fence, will break, and the panels remain attached to the posts B, and yielding freely to the action of the water; so also the braces E will be held by the pins A'. As there will be no longer resistance when exposed to the current, the fence will not be carried away, and, on the subsidence of the flood, the fence can be easily restored to position by putting in new pins C.

I do not claim the panels, nor the braces alone nor in combination; but

What I do claim, is—

The mode of constructing the fence, and sustaining it by pins C at the top of the braces, so arranged, in relation to the other parts, that they will first yield to force of currents of water, and permit the panels and braces to swing freely in the stream on the pins by which they are attached to the ground-posts, substantially as set forth.

JOHN B. JOHNSON.
